CONTAINER

Edward O. Then, Newark, N. J., assignor to
American Can Company, New York, N. Y., a
corporation of New Jersey

Application June 6, 1941, Serial No. 396,930

4 Claims. (Cl. 220—54)

This invention relates to a sheet metal can or container having a tearing strip set off by score lines cut in the outer wall fold of a body extension and has particular reference to an integral hinge element located in a longitudinal soldered lock seam extending between the end closure members which are secured to the body wall and to the body extension to provide a body of increased strength, the removal of the tearing strip providing a hinged reclosure for the container.

The instant invention contemplates an improved hinge construction in a tearing strip container having a folded body extension as an integral part of a body wall formed with a longitudinally soldered lock side seam extending between end closure members secured to the body parts such as is described in my copending application of even date and identified by Serial Number 396,929, now Patent No. 2,325,084.

The invention relates to a construction of a hinged closure can in which the can body wall proper is fully locked and soldered so that the lock seam feature extends between the ends of the can. Such a can also is provided with an integral folded body extension which does not affect the full locking side seam principle for the can throughout its entire height. The body extension in this can is cut away at the side seam and the usual solder applying operation may be utilized in the manufacture of the can since the cut-away body extension walls are removed where the solder is being applied to the side seam. The hinging element includes hinge tabs formed integrally with the body wall and secured into the end closure joint.

An object of the invention is the provision of a tearing strip container having a fully locked body, the side seam of which extends from one end of the can to the other, such a can having an additional double wall body extension adjacent its upper end, and having hinge tabs struck out from the body wall proper or from the body extension so that upon removal of the tearing strip in opening the can such hinge tabs become effective to produce a hinged reclosure member for the opened can.

Another object of the invention is the provision of a can of the character described wherein the double folded body wall extension is cut away adjacent the side seam to permit application of solder for the fully locked side seam and wherein the hinging elements include a hinge tab projected from the body wall adjacent such body extension and on opposite sides of the side seam, such tabs being seamed into the end joint.

A still further object of the invention is the provision of a can of the character described wherein the hinging element includes a single hinge tab cut from the inner wall of the body extension and folded into position between the

walls of the body extension at the locked seam where it is secured in the upper end joint.

Numerous other objects and advantages of the invention will be apparent as it is better understood from the following description, which, taken in connection with the accompanying drawings, discloses a preferred embodiment thereof.

Referring to the drawings:

Figure 1 is a perspective view of the sealed container embodying the present invention;

Fig. 2 is an enlarged fragmentary view showing the upper end portions of a flat blank from which the body of the container is made;

Fig. 3 is a fragmentary perspective view of opposite upper ends of the body blank shown in Fig. 2 after being folded and after the blank has been formed into tubular shape and illustrating integral hinge tabs projecting from the body wall proper;

Fig. 4 is a fragmentary face view of that part of the container body shown in Fig. 3 after being locked, lapped and joined together;

Figs. 5 and 6 are enlarged sectional details at the longitudinal joint of the container body, as viewed, respectively, along the lines 5—5 and 6—6 in Fig. 4;

Fig. 6a is a sectional detail taken through the top double seam and the adjacent folded body wall of the sealed container;

Fig. 7 is a side elevation of the upper portion of the container illustrated in Fig. 1, showing it in a partially open position following the removal of the tearing strip;

Fig. 8 is a view similar to Fig. 7 showing the container further opened by hinging of its reclosure member;

Fig. 9 is an enlarged fragmentary view similar to Fig. 2 and showing a modified form of flat blank wherein the hinge tab is cut from a different wall part of the container body; and

Fig. 10 is a fragmentary perspective view of opposite upper ends of the body blank shown in Fig. 9 after being folded and after the blank has been formed into tubular shape.

As a preferred embodiment of the invention the drawings illustrate a cylindrical sheet metal container 11 (Fig. 1) having a tubular body 12 the opposite edges of which are joined together in a longitudinal fully locked side seam 13. The body also has a circumferential multiple folded wall 14 adjacent its upper end. Top and bottom end closures 15 and 16 are secured to the body in double end seam joints 17.

The body 12 is produced from a flat body blank 18 (Fig. 2). Such a body blank may be uncoated on one or both sides or printed or lithographed as desired as in the case of decorated containers. The body blank 18 is formed with a tearing tongue 19 at one edge of the blank and with a projecting hinge tab 22 which is spaced below the

tongue at the same edge. A projecting hinge tab 23 is formed on the opposite edge of the body blank.

The body blank 18 comprises a major body wall section 24, an integral intermediate body wall folded section or extension 25 and an integral outer wall fold or extension 26. The hinge tabs 22 and 23 extend up from the body wall section 24 and are notched or slit in a suitable manner as at 27, 28 to separate each tab from the intermediate body wall extension 25. This provides for a distinct line of bend or fold 29 between the major body wall section 24 and the intermediate wall extension 25. A line of bend or fold 32, which is parallel to the line of bend 29 and also to the upper end of the sheet, designates the boundary between the sections 25 and 26.

The outer wall extension 26 has parallel score lines 33 which set off a tearing strip 34. Such a tearing strip terminates in the tearing tongue 19 at one end of the blank. A V-shaped notch 35 is cut in the edge of the wall extension 26 on each side of the tearing tongue, the apex of each notch leading directly into the score line. Lines of bend or fold 36, 37 set off opposite marginal edges 38, 39 of the body blank section 24.

Fig. 3 of the drawings illustrates the upper portions of the two edges of the body blank 18 after the intermediate and outer wall extensions 25 and 26 have been folded along the lines of bend 29, 32 and have been shaped into the double wall extension 14. The folded body is then formed into tubular shape. This view also shows how the intermediate and outer wall extensions are cut away at the longitudinal seam region leaving the top of the hinge tabs 22 and 23 in the same horizontal plane as the top of the outermost wall 26.

The marginal edge 38 is folded inwardly to form the outer hook section for the lock seam of the container body. The marginal edge 39 likewise is folded but in an outwardly direction to form the inner hook of the seam. The tongue 19 may be folded back upon the outermost wall extension 26 where it is disposed parallel with the outer wall. To avoid crystallization of the stock, the bent section of the tongue may be formed as an open loop.

Fig. 3 of the drawings discloses that a rolling or similar operation has been performed on the major body wall surface 24 so that this body wall above a line of depression 42 has been necked-in to provide a depressed pocket 43 for a purpose hereinafter described. The side seam region, however, is not depressed but remains unaltered.

The inner and outer hook sections of the folded marginal edges 38, 39 upon being interlocked when the can body is fully formed, constitute the longitudinal lock seam. As will be subsequently explained, such a seam extends substantially the full body height of the container. At such completion of the can body, the hook sections of the side seam are bumped down in the usual manner to produce the completely formed lock seam. It is preferable during such a bumping operation, to also squeeze the double wall extension sections 25, 26 together so that they fully seat in the pocket 43 as in Fig. 1. When thus formed the exterior surface of the outermost wall is flush with the outer surface of the body wall proper.

Figs. 4, 5 and 6 of the drawings show how the opposite ends of the outermost wall extension 26 in the fully bumped container body overlap upon the hinged tabs 22 and 23 adjacent the

longitudinal side seam. Such a container body is now ready for soldering of the side seam and for sealing of the body extension edges. The fluxing and soldering of the longitudinal side seam may be done in the usual manner. The solder is usually applied to the exterior of the body by a solder roll and the construction of the fully bumped container which includes a continuous flush surface along the side seam, permits such application.

The open space between adjacent edges of the cut-away wall extensions 25, 26 together with the space afforded by the turned-back tongue 19 insures unrestricted access to the seam crack by the soldering roller. Such a solder line therefore extends as an unbroken band for the full length of the lock seam on the container body wall. At the same time the solder enters between the edges at the cut-away body walls of the extension and also bonds such walls together and secures the walls to the container body wall in a hermetic seam.

The fully soldered container body is now ready to receive its bottom end 16 (Fig. 1). Such a body may be flanged in the conventional manner, whereupon the bottom is double seamed or otherwise secured in position to form the end seam 17. This prepares the can for receiving its contents. When the container is filled with its contents, the top end closure 15 is double seamed or otherwise secured to the upper end of the outermost wall extension 26 and to the extended hinged tabs 22 and 23 in the end seam 17. This completely seals the container with its contents. Such sealed containers usually have a slotted key 44 secured to the cover 15, as by welding, for convenience in opening.

When the container is to be opened, the tearing strip 34 may be removed by engagement of the slotted key 44 with the turned back tearing tongue 19. By reason of the tongue being turned back in the winding-off direction only a partial turn of the key, after it has been fully applied, suffices to fully seize the tearing strip so that it is easily broken along the score line.

Removal of the tearing strip 34 from the outermost wall extension opens the container and leaves only the hinged tabs 22, 23 as a connection with the open container (Figs. 7 and 8). Since the hinged tabs constitute extensions of the body proper and comprise the outer layers of the completed can they permit unrestricted outward bending at the side seam. This permits raising the cover at the opposite side to remove the container contents. The flexibility of the hinged tabs 22 and 23 permit repeated opening and closing of the cover as a reclosure member.

The reclosure upon being swung into closed position on its hinged connection allows the severed marginal portion of the outermost wall extension 26 which still remains secured to the cover, to frictionally engage with and over the intermediate wall extension 25. At the same time a depending annular wall 45 of the cover 15 frictionally engages inside of the smooth body wall 24 with an interior friction fit.

Figures 9 and 10 of the drawings show a modified form of the invention wherein the hinging element comprises a single hinge tab 46 which is cut at one edge of a body blank 47. This body blank is similar in certain respects to the blank 18 (Fig. 2) and also includes a tearing tongue 48 which is spaced above the projecting hinge tab. Such a hinge tab, however, may be formed at the opposite edge of the sheet if desired and will

function in the same manner as the form shown.

The body blank 47 like body blank 18, has a major body wall section 49, an intermediate body wall extension 52, and an outer body wall extension or section 53. The hinge tab 46 is notched or slit at 54, 55 in the material at the end of the blank 49 to separate it from the intermediate body wall extension 52 so that it may be folded as an integral part of the latter extension along a line of bend or fold 56. The opposite edge of the sheet is notched or slit as at 57 so that a distinct line of bend or fold 58 may be provided between the major body wall section 49 and the intermediate wall extension 52. Similarly a line of bend 59 which is parallel to the line of bend or fold 58 designates the boundary between the wall extensions 52 and 53.

Substantially all other details present in the body blank 47 (Fig. 9) have hereinbefore been illustrated and described in connection with the body blank 18 of Fig. 2. Fig. 10 of the drawings shows the body blank 47 folded and formed in tubular shape as by the same procedure as was the body blank 18 of Fig. 3. The former view shows the hinge tab 46 folded upwardly along the line of bend 56 and placed between the intermediate wall extension 52 and the outer wall extension 53.

The forward or free end of the hinge tab 46 is arranged to extend out and lap-over the outermost wall extension 53 at the opposite edge of the body and to be secured thereto when the lock side seam is soldered. The hooked edges of the fully prepared body 47 are finally interlocked in the conventional manner and all the subsequent operations which follow to complete a sealed container are similar to those which have been hereinbefore described.

Opening of a sealed container embodying a single hinge tab is the same as when two hinge tabs are used and provides a similar hinge connection and reclosure feature.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A sealed metallic container, comprising a tubular body having a longitudinal side seam and having an integral folded double wall body extension at its upper end and on the outside, the outermost wall of the body extension containing a tearing strip set off by score lines and terminating in a tongue, a bottom end closure secured to the lower end of said body, a top end closure secured to the outermost wall of said extension, said tubular body wall being bent inwardly to provide a flush exterior surface for said outermost extension wall and the tubular body wall below said extension wall, said longitudinal side seam extending between the top and bottom end closures as a smooth continuous section through said bent wall part to close and strengthen the body, said body wall having a plurality of integral overlapping and outwardly projecting hinge tabs constituting longitudinally disposed prolongations of said side seam embodied in said top end and body connection, said tearing strip being remov-

able to open the container to adapt said tabs for hinging action of said top and closure thereon with its attached outermost body wall extension as a reclosure member having frictional engagement with the inner wall of said body extension.

2. A hinge cover tearing strip metallic container of the reclosure type, comprising a tubular body having an integral circumferential multiple fold in its wall adjacent one end, the outermost of said folded walls containing a tearing strip set off by score lines, and an end closure secured to the said outermost wall, said body having a longitudinal lock side seam extending to the joint between said body and closure to close and strengthen the body, the inner wall of said folded walls having an integral projecting hinge tab disposed in the plane of said inner wall and extending longitudinally outwardly from and disposed in alignment with the lock portion of said side seam, said hinge tab being embodied in the said end and body connection, said tearing strip being removable to open the container after which said integral hinge tab provides a hinged reclosure member having frictional engagement with the opened container.

3. A sealed metallic container comprising a tubular body having at its upper end an integral folded double wall body extension on the outside, the outermost wall of the body extension containing a tearing strip set off by score lines and terminating in a tongue, a bottom end closure secured to the lower end of said body, and a top end closure secured to the outermost wall of said extension, said body having a longitudinal soldered side seam extending between the top and bottom end closures to close and strengthen the body, said body wall having a plurality of integrally formed overlapping and outwardly projecting hinge tabs disposed adjacent said side seam, said hinge tabs being embodied in the innermost wall of said top end and body connection and extending longitudinally outwardly from said side seam, the double wall body extensions being cut away and soldered adjacent and in substantial alignment with said side seam, said tearing strip being removable to open the container, whereby the top end closure with its attached outermost body wall extension provides a hinged reclosure member having frictional engagement with said tubular body wall and said body extension.

4. A hinged cover tearing strip metallic container of the reclosure type, comprising a tubular body having a circumferential double fold body extension integral with and disposed outside of the body adjacent one end, the outermost of said folded wall extension containing a tearing strip set off by score lines, and an end closure secured to the said extension wall, said body having a longitudinal lock side seam extending to the joint between said body and closure to close and strengthen the body, said body wall having a plurality of integral overlapping and outwardly projecting hinge tabs disposed on opposite sides of said side seam and embodied in said end and body connection, said hinge tabs extending longitudinally outwardly from and disposed in alignment with the lock portion of said side seam, said tearing strip being removable to open the container, whereby to adapt said tabs for hinging action of said end closure as a reclosure member, said inner wall of the body extension of said opened container providing a seat for said reclosure member.

EDWARD O. THEN.
